DESIGN FOR A LADY'S HAT

Hyman Rosen, New York, N. Y.

Application November 18, 1936, Serial No. 65,997

Term of patent 3½ years

To all whom it may concern:

Be it known that I, Hyman Rosen, a citizen of the Union of the Soviet Socialist Republics, residing at 901 Jennings Street, Bronx County, city and State of New York, have invented a new, original, and ornamental Design for a Lady's Hat, of which the following is a specification, reference being had to the accompanying drawing forming a part thereof.

In the drawing:

Fig. 1 is a top perspective view of a hat illustrating my new design.

Fig. 2 is a front perspective view thereof.

Fig. 3 is a back perspective view of the hat.

I claim:

The ornamental design for a lady's hat substantially as shown.

HYMAN ROSEN.
